(57) **CLAIM**

The ornamental design for brace components, as shown and described.

DESCRIPTION

FIG. 1 is a front elevational view of the brace components of the present invention;

FIG. 2 is a front elevational view of the brace components of FIG. 1, illustrating the brace components in an alternative position;

FIG. 3 is a rear elevational view of the brace components of FIG. 1;

FIG. 4 is a left-side elevational view of the brace components of FIG. 1, the right-side elevational view being a mirror image thereof;

FIG. 5 is a bottom plan view of the brace components of FIG. 1, the top plan view being a mirror image thereof;

FIG. 6 is a front elevational view of a component part of the brace component of the present invention;

FIG. 7 is a rear elevational view of the component part of FIG. 6;

FIG. 8 is a left-side elevational view of the component part of FIG. 6, the right-side being a mirror image thereof;

FIG. 9 is a bottom plan view of the component part of FIG. 6;

FIG. 10 is a top plan view of the component part of FIG. 6;

FIG. 11 is a front elevational view of another component part of brace component of the present invention;

FIG. 12 is a rear elevational view of the component part of FIG. 11;

FIG. 13 is a left-side elevational view of the component part of FIG. 11, the right-side elevational view being a mirror image thereof;

FIG. 14 is a bottom plan view of the component part of FIG. 11; and,

FIG. 15 is a top plan view of the component part of FIG. 11. The broken line showing of component parts is for illustrative purposes only and forms no part of the claimed design.
